UNITED STATES PATENT OFFICE.

LOUIS ORIGONE, OF MARSEILLE, FRANCE.

FABRIC MADE OF SCRAP FELT OR OTHER PLIANT MATERIAL.

Application filed May 7, 1927, Serial No. 189,685, and in France March 19, 1927.

The object of the present invention is a fabric made of the waste of felt, leather, wax cloth, rubber, cloth or the like pliant material, said fabric being adapted for making garments, footwear, hat ornaments and linings, sporting, travelling, and furnishing goods. The fabric consists in a plurality of elements, each element consisting of a strip of pliant material and having at each end 10 an eye, said elements arranged in horizontal and vertical rows, said vertical rows composed by folded strips, two opposite strips of two neighbouring vertical rows being connected together by at least one horizontal strip, the next folded strip passing with its central portion through the eye of the horizontal strip and through both eyes of the preceding strip of the vertical row.

In the accompanying drawings by way of example several embodiments of the object of the invention have been shown. Figs. 1 to 20 4 and 6 to 8 show several perspective views of seven different embodiments whereas Fig. 5 shows details respecting four different forms of the elements or strips of the fabric.

Scrap or waste material of felt, leather etc. is cut out in the shape of strips. The strip A' of Fig. 5 has diamond shaped ends the central portion being rectilinear; the strip A'' has tail shaped ends, the central portion being rectilinear; strip A''' has square shaped ends, both sides of the central portion being concave shaped; the strip A'''' has pointed ends with curved sides, the central portion being on both sides concave shaped.

Each end of each strip has a hole C of a diameter sufficient to allow, without too great a deformation, the introduction of another strip into both the openings.

In Fig. 1 the fabric is composed of vertical and horizontal rows of strips. Each folded strip A of a vertical row passes with its central portion through both eyes of the preceding strip. All strips are of identical size. Two opposite strips of the first and third vertical row, seen from the left, are connected together by a horizontal stretched strip B the next folded strip passing with its central portion through the eye of the horizontal unfolded strip and through both eyes of the preceding strip of the same vertical row. The end of each horizontal strip lies between both ends of a folded strip. The second vertical row of folded strips is

not connected by horizontal strips, but each strip connects the two folded strips of the first and third row together passes through the folded strip of the second row. The folded strips of the third and fourth rows 60 are connected together by horizontal strips. The fourth, fifth and sixth vertical rows are made in the same way as the three first vertical rows and so on.

The so constituted fabric is finished therefor by a horizontal row of folded strips.

Fig. 2 shows a fabric the vertical rows of folded strips A being connected together by horizontal unfolded strips B placed crosswise. The fabric is lined by a horizontal 70 row of folded strips.

In Fig. 3 two vertical rows of folded strips A are connected together by horizontal rows of folded strips, always two folded strips of a horizontal row connecting together two 75 opposite folded strips of two neighbouring vertical rows. This fabric has the advantage of constituting a tighter web, because between both ends of each folded strip of a vertical row two folded strips of a horizontal 80 row are seized by the next strips of the same vertical row. Of course the folded strips of the vertical lining rows of the fabric seize only a single folded strip of a horizontal 85 row. In Fig. 4 the vertical and horizontal rows are inclined, forming lozenges. Each side of each lozenge is formed by two folded strips A, the one of them passing with its central portion through both eyes C of the other one. In each corner of a lozenge the 90 central portions of two folded strips are passed through the four eyes of two folded strips of the next upper lozenge.

In Fig. 6 only the second next folded strips A of the vertical rows are bound together by horizontal unfolded strips B.

In Fig. 7 each folded strip A of a vertical row is connected by an unfolded strip B of a horizontal row to the opposite folded strip of the neighbouring vertical row.

Fig. 8 shows a part of a ladies' market bag made of a fabric like that shown in Fig. 7, the fabric being tighter, because the horizontal unfolded strips B have a width equal to the length of a strip in folded state. 105 The carrying-handles are made of folded strips A.

It is, of course, quite possible to obtain all kinds of other patterns, not shown on the drawings.

These strips may have different colours and will allow of obtaining very artistic fabrics.

Having thus particularly described and ascertained the nature of my said invention, I declare that what I claim is:—

1. In a fabric a plurality of elements, each element consisting of a strip of pliant material and having at each end an eye, said elements arranged in horizontal and vertical rows, said vertical rows composed by folded strips, two opposite strips of two vertical rows being always connected together by at least one horizontal strip, the next folded strip passing with its central portion through the eye of the horizontal strip and through both eyes of the preceding strip of the vertical row.
2. In a fabric a plurality of elements, each element consisting of a strip of pliant material and having at each end an eye, said elements arranged in horizontal and vertical rows, said vertical rows composed by folded strips, two opposite strips of two neighbouring vertical rows being always connected together by an unfolded strip, the next folded strip passing with its central portion through the eye of the horizontal unfolded strip and through both eyes of the preceding strip of the vertical row, and the end of the horizontal strip laying between both ends of said preceding folded strip.

3. In a fabric a plurality of strips of pliant material, each strip having at each end an eye, said strips arranged in horizontal and vertical rows, said vertical rows composed by folded strips, two opposite strips of two neighbouring vertical rows being always connected together by an unfolded strip, the next folded strip passing with its central portion through the eye of the horizontal unfolded strip and through both eyes of the preceding strip of the vertical row, each horizontal edge of the fabric being formed by a row of folded strips.

4. In a lady's market bag, a fabric constituted by a plurality of strips of pliant material each end of each strip having an eye, said strips arranged in horizontal and vertical rows, said vertical rows composed by folded strips, two opposite strips of two neighbouring vertical rows being always connected together by an unfolded strip, the next folded strip passing with its central portion through the eye of said horizontal unfolded strip and through both eyes of the preceding strip of the vertical row, each edge of the fabric lined by a row of folded strips, and a carrying handle being made of rows of folded strips.

In testimony whereof I have signed my name to this specification.

LOUIS ORIGONE.
